WINDOW CONSTRUCTION

Alfred O. Williams, Battle Creek, Mich., assignor
to Clark Equipment Company, Buchanan,
Mich., a corporation of Michigan

Application November 1, 1939, Serial No. 302,280

6 Claims. (Cl. 189—72)

This invention is primarily concerned with a window construction for use on vehicles such as street cars, busses and railway coaches.

One of the primary objects of the present invention is to provide a single window construction which is so arranged as to be mounted entirely on the outer surface of the vehicle and to be guided or vertical movement thereon.

It has heretofore been necessary to provide window framing and sash in vehicles of this type, which is an integral part of the vehicle body construction and which requires the removal of substantially the entire window frame in order to provide access for changing the glass or adjusting the mechanism.

In the present construction I provide an arrangement whereby the window may be removed readily from the exterior of the vehicle when so desired, and which is so designed as to provide ample sealing surfaces for protection against drafts and the entrance of dust or moisture.

Another object of the present invention is to provide a window construction which is of pleasing design conforming to the streamlined appearance of the vehicle, and which is so arranged that it opens by a downward vertical movement as compared with previous designs in which the lower edge of the window was raised above the window sill. In this connection the present invention eliminates the necessity of providing a recess or a well into which the lower portion of the window moves when it is opened within the car body, as the present construction allows this movement of the window without requiring any sill, recess or the like.

Other objects and advantages of the present invention will appear more fully from the following detailed description which, taken in conjunction with the accompanying drawings, will disclose to those skilled in the art the particular construction and operation of a preferred form of the invention.

In the drawings:

Figure 1 is an elevational view of a window construction embodying the present invention;

Figure 2 is a vertical sectional view taken substantially on the line 2—2 of Figure 1; and

Figure 3 is a transverse section taken substantially on line 3—3 of Figure 1.

Considering the drawings in detail, the car body is indicated generally at 5, and as shown, is provided with a window opening 6 defined by an upper channel shaped frame member 7 and a lower sill member 8. The upper member 7 is preferably formed of an extruded light-weight

metal section, such as aluminum or the like, and has the inwardly disposed lip portion 9 forming a recess with the interior sheathing 10 of the car to provide for the insertion of advertising cards or the like, the lower edges of which are disposed in the recess 11.

The outer leg portion of the channel member 7 is supported in position by being riveted, as indicated at 12, to the outer shrouding 13 forming the outer surface of the car body, and an angle section 14 is also secured in position by means of the rivet 12 over the outwardly projecting lip 15 of the member 7. The window header 7 forms with the depending flange portion 16 of the member 14 a downwardly opening channel 17 adapted to receive the sealing member 18, which may be formed of rubber or other suitable resilient sealing material. This sealing member 18 is held in position by means of the inwardly directed projections 19 and 20 carried by the members 7 and 14 which firmly support the strip 18 in fixed position in the upper end of the channel, the member 18 having a lower flared portion 22 projecting below the projections 19 and 20.

The sill member 8 has a downwardly extending projecting flange 23 which is adapted to have riveted thereto the lower stop member 24 for the window, as by means of rivets 25. The lower

30 rivet 25 also secures the outer body closing member 26 intermediate the members 23 and 24, the member 26 forming a continuation of the body surface and being substantially in alignment with the member 13.

35 The flange 23 and the member 24 are provided intermediate their ends with boss portions, indicated generally at 27, adapted to receive the screws 28 which secure the molding strip 29 in position, this strip 29 forming the belt molding

40 for the vehicle body. At its upper end the member 24 is provided with an outwardly projecting flange 30 having a substantially centrally located longitudinal rib 32 for a purpose to be herein-after described. The window glass indicated

45 generally at 33 is contained within a frame comprising an upper header member 34 of fabricated construction having a channel shaped depending recess 35 receiving the upper edge of the window glass, the glass being cemented therein by means

50 of suitable resilient sealing material 36. At the upper end of the header 34 there is provided a second channel shaped recess 37 adapted to receive a rubber sealing strip 38 which is locked therein by means of the projections 39, the sealing member 38 having an upwardly convex sur-

face adapted to be received in the convex recessed flaring portion 22 of the sealing strip 18. Thus, when the window is in closed position an effective dirt and moisture proof seal is provided between the members 18 and 38.

The lower edge of the window glass 33 is sealed within a lower frame member 34 of the same construction as the header member 34, but which is inverted in position. This member has a corresponding recess 35 in which is sealed the lower edge of the glass 33 by means of the sealing material 36. At its lower end the member 34 is adapted to receive a sealing strip 40 which is secured therein by means of the projections 39 in the channel 38, but which is provided with a longitudinal recess portion 42 adapted to engage over the rib 32 of the flange 30 to provide an effective seal therewith. The member 40 is also provided with an inwardly directed lateral extension 43 which, when the window is in raised position engages the under surface of a longitudinally extending channel strip 44 secured to the sill member 8 and carrying mohair or felt sealing means 45. The weatherstripping 45 is thereby pressed against the inboard surface of the lower member 34 when the window is in closed position, and is closed at its lower end by means of the extension 43 of the sealing strip 40.

The side framing for the window is provided by means of guide members secured to the frame posts 48 defining the window frame. The forward vertical guiding member comprises the arcuate strip 49 which, at its forward edge, is bent inwardly to engage against the body surface 13 and is spaced away from the flange portion 50 of the vertical post by means of the spacing strip 52 which is secured to the flange 50 by means of the rivets 53 and which is tapped to receive the screws 54 for securing the guide strip 49 in position. Mounted within the channel 55 formed between the strip 52, the car body surface 13 and the rear edge of the member 49 is a guide supporting member 56 formed of thin metal stock bent into a channel shape and carrying on the inner surface thereof weatherstripping material 57. This material may be cemented or otherwise secured in the supporting member 56 mounted in the channel 55. The side edges of the window are sealed by means of the sealing material 60 69 in similar frame members 62 formed of thin sheet metal sections and shaped to be received in the channel 55 in sealing engagement with the weatherstripping 57.

Preferably, the window construction is so arranged that the windows are provided in pairs separated by a center member comprising the plate 63 secured through the spacing member 64 to the center vertical post member 65. This forms oppositely directed vertical channels 66 within which are received the channel shaped supporting members 56 carrying the weatherstripping 57. It will thus be seen that the opposite vertical edges of the window pane 33 are sealed in frame members 62 which in turn are received for sliding engagement in channels containing the weatherstripping 57 which effectively seals the side frame members against the passage of dust or moisture, and provides a completely sealed window construction when the window is in closed position.

The window is locked in closed position by means of the latch mechanism 70 illustrated diagrammatically in Figure 1 having a latch projection 72 controlled by the latch figures 73 adapted to engage in notches formed in a large

bearing 74 secured to the upper end of the side post members 48 and 65 interiorly of the window. By releasing the latches 72, the window can be moved into intermediate open positions to provide various spacing of the upper edge of the window with respect to the header member 7. When in full open position the bottom sealing strip 40 of the window frame is moved downwardly to rest on the flange 30, thereby supporting the window on this flange and in sealing engagement therewith, the upper edge of the window being then disposed an appreciable distance below the header 7, the window being supported in this position by the side guide channels 55 and 66.

With this type of construction, it is apparent that the window may be readily removed by removing the screws 54 and the screws 68 which support the plate 63. This removes any lateral guide for the window itself, and since the window has no confining means at the lower end thereof, it may be moved downwardly and outwardly by release of the latches for complete removal from the car body to repair or replace the sealing means or to replace damaged window glass.

It will be noted that the window frame members 7, 8 and 14, as well as the supporting member 24, are formed of extruded metal sections which may, if desired, be of aluminum or the like, whereby the configuration can be readily controlled to provide the desired type of section with the desired projections to insure locking of the sealing means in position, and proper defining surfaces for the window construction. Similarly, the window strip supporting members 56, as well as the window frame members 34 and 62 are formed of thin metallic sections which may be rolled or otherwise fabricated to the desired shapes to insure control of the sealing means carried by the window itself, such as the sealing means 38 and 40 and proper engagement with the window stripping 57 in the side channels. Further, it will be noted that the framing members 34 and 62 are hollow or tubular in form, providing a very light weight construction so that the window may be readily moved into the desired position without any great expenditure of energy.

I am aware that various changes may be made in certain details of the present construction without in any way departing from the underlying principles thereof, and I therefore do not intend to be limited except as defined by the scope and spirit of the appended claims.

I claim:

1. In a window construction for a vehicle body having a window opening in the side walls thereof, a pair of vertically extending side rails on opposite side edges of said openings projecting outwardly of the vertical body surface and having facing channel portions, a horizontal header across the top of said opening offset outwardly of the body surface and comprising a downwardly opening channel having a lower concave surface, a window having defining frame members and adapted to slide vertically in said side rails, the upper frame member having a convex surface adapted to engage in said header surface, and a horizontal ledge spaced beneath the lower edge of said window opening for supporting the lower frame member of said window when in lowered position in said side rails, said ledge projecting laterally outwardly from the plane of said body surface and supporting the entire

weight of said window when in lowered position.

2. A window arrangement adapted to be mounted on the exterior surface of a vehicle body about a window opening, comprising a header member defining with said surface a downwardly opening channel, a pair of parallel vertical side rail members comprising plates mounted in outwardly spaced relation to said surface to define therewith facing channels, a window adapted to slide vertically in said side rails, means in said header channel sealing the upper edge of said window therein when in closed position, and a laterally projecting ledge disposed on said surface and spaced below said header member a distance greater than the height of said window for supporting said window in open position.

3. The arrangement of claim 2 wherein the lower edge of said window is provided with a resilient compressible sealing member having a concave depending portion adapted to engage said ledge and a laterally inwardly directed flange adapted to engage and wipe along said body surface during vertical movement of the window.

4. The combination, in a vehicle body having vertically slideable windows mounted in spaced pairs on the outer surface thereof about the defining edges of the window openings, of means for forming a common side rail support for the adjacent vertical edges of each pair of windows comprising a vertical outwardly projecting spacer strip secured to the outer surface of the vehicle body between said openings, and

5 a plate secured over said spacer strip and disposed in a plane parallel to said body surface and spaced outwardly thereof, said plate defining with said surface oppositely facing channels separated by said spacer strip.

10 5. Means forming a side rail frame for a window mounted on the outer surface of a vehicle body comprising a vertically extending spacer strip secured to said outer surface, a plate member secured to said strip having a planar portion overlying one side of said spacer to define with said surface a vertically extending longitudinally facing channel, said member having a curved portion overlying the opposite side of the spacer strip with its forward edge engaging said outer body surface.

15 6. A window header construction for windows mounted on the exterior surface of a double walled vehicle body comprising a channel-shaped member secured within and closing the walls across the top of the window opening and having an outwardly directed horizontal flange, a cooperating member having oppositely extending offset flanges, one flange being mounted on the exterior wall of said body above the flange of the channel member and the other flange extending downwardly from the outer edge of the flange of the channel member to define therewith a downwardly opening channel, and resilient sealing means locked in the base of said last-named channel for sealing engagement with the upper edge of said window.

ALFRED O. WILLIAMS.
